CLAIM

The ornamental design for a food and beverage carrier, as shown.

DESCRIPTION

FIG. 1 is a perspective view of a food and beverage carrier showing the new design;

FIG. 2 is a front elevation view of the carrier depicted in FIG. 1;

FIG. 3 is a side elevation view of the carrier;

FIG. 4 is a rear elevation view of the carrier depicted in FIG. 1;

FIG. 5 is an opposite side elevation view of the carrier depicted in FIG. 1;

FIG. 6 is a top plan view of the carrier depicted in FIG. 1; and,

FIG. 7 is a bottom plan view of the carrier depicted in FIG. 1.
